[57] CLAIM

The ornamental design for a syringe, as shown and described.

DESCRIPTION

FIG. 1 is an exploded front perspective view of a syringe showing my new design, with the cap removed for clarity of illustration;

FIG. 2 is a rear perspective view thereof;

FIG. 3 is a front elevational view thereof shown with the cap removed and with the rear being a mirror image;

FIG. 4 is a side elevational view thereof shown in assembled condition and with the opposite side being a mirror image;

FIG. 5 is a bottom plan view of FIG. 3;

FIG. 6 is a top plan view thereof;

FIG. 7 is a front elevational view of the cap element, with the opposite sides being identical thereof, and shown separately for clarity of illustration only;

FIG. 8 is a bottom plan view of FIG. 7; and

FIG. 9 is a top plan view of FIG. 7.

FIG. 1.

FIG. 2.

FIG. 3.

FIG. 4.

FIG. 5.

FIG. 6.

FIG. 7. FIG. 8. FIG. 9.
